Inventor

Albert Paul Cochrane

By his Attorney

J. H. Landberg

UNITED STATES PATENT OFFICE.

ALBERT PAUL COCHRANE, OF BROOKLYN, NEW YORK, ASSIGNOR TO HERVEY, BARBER & MCKEE, OF NEW YORK, N. Y., A FIRM COMPOSED OF EVERETT P. HERVEY, ARTHUR WILLIAM BARBER, AND LANIER MCKEE.

CONTAINER.

1,264,015.

Specification of Letters Patent. Patented Apr. 23, 1918.

Application filed March 21, 1917. Serial No. 156,245.

To all whom it may concern:

Be it known that I, ALBERT PAUL COCHRANE, a citizen of the United States, and a resident of the borough of Brooklyn, 5 in the county of Kings and city and State of New York, have invented a new and useful Container, of which the following is a specification.

The invention is an improvement in containers and corner-pieces, more especially of the type disclosed in my Reissue Patent No. 14,294 of May 1, 1917, the object being to effect simplification and to provide a corner fastener which can be operated from the 15 outside and affords more room in the interior.

In the accompanying drawings:

Figure 1 is a perspective view of the container partly assembled; Fig. 2 is an inside view of one of the corner fastenings; Fig. 3 is a side view of the same; Fig. 4 is a section on the line 4—4 of Fig. 2; Fig. 5 is an outside perspective view of an assembled corner; Fig. 6 is an inside perspective view of an assembled corner; Fig. 7 is a vertical section through a bottom corner, assembled; Figs. 8 and 9 are detail views of the inner member of a corner fastening; Fig. 10 is a perspective view of the box 25 collapsed; Fig. 11 is a vertical longitudinal section through the same; Fig. 12 is a vertical section through a lower corner, illustrating a slight modification; Fig. 13 is a perspective view of a corner portion of 30 one of the container sections formed as in Fig. 12; Fig. 14 is a perspective view of an alternative form of end section; and Fig. 35 15 is a side view of a slightly different form of nut.

The container is a hollow parallelepiped built up of separate side or wall sections 1, 2, 3, 4, 5 and 6, preferably of sheet metal and having inturned edge flanges 7. For purposes of distinction the sections may be referred to as end sections 1 and 2, side sections 3 and 4, bottom section 5, and top or cover section 6. The flanges enable the sections to be mutually staying when erected and afford anchorage for the corner fastenings as in my prior patents.

The corner fastenings here employed comprise outer and inner hollow virtually pyramidal members 8 and 9, fitting the exterior and interior apical corners of the

container. Each inner member has an 55 apical projection 10, in the present instance a screw stem formed or united integrally with the member, and the outer member or cap has an apical opening or recess 11 to receive the stem. A ball nut 12 screwed 60 onto the end of the stem and against a flat bearing face 13 on the cap constitutes both a means of applying clamping pressure and a buffer and skid. This nut may have angular wrench-receiving faces 17 65 formed on a reduced neck, as shown in Figs. 3 and 4, for example, or a clamping boss having less projection may be produced as shown in Fig. 15 by forming the wrench faces on one-half of the ball 12a.

In 70 the extreme corners of the sections are provided with registering or complementary recesses forming openings 14 at the apical corners when the container is set up, for the stems 10 to pass through. In one or 75 more of the sections, particularly the cover section or the one last applied in the closing of the box, the ends of the flanges may be separated by spaces or slots 15, constituting lateral entrances to such openings, capable 80 of sliding over the necks of the stems 10 of the inner members 9, which may thus be positioned before the cover is put on. During this operation and until the nuts are screwed on, the said inner members may be held 85 in place by virtue of their stems being a somewhat tight fit in the corner openings of the end and side sections 1—4. Or, the necks 16 of these stems may be slightly reduced to pass through the slot entrances, the 90 outer portions of the stems being larger than the corner openings, so that the inner members are keyed in place before the nuts are put on. Wherever this construction is 95 employed the slots 15 are required.

The sections are preferably so graduated in size that the two side sections 3 and 4 may nest one into the other in the collapsed condition, and both into the bottom section, while the end sections 1 and 2 nest 100 into each other and both into the side sections, while the top section fits over all. This involves the end sections being received inside the side sections when erected, as shown in Fig. 1. Manifestly the order 105 of nesting sizes of the sections and their arrangement inside or outside of each other when erected may be varied, while

still retaining the principle of graduated sizes whereby all but one of the flanged sections nest successively together with their flanges all pointing in the same direction, the last section receiving all of them with its flanges pointing in the opposite direction.

Fig. 14 illustrates the fact that it is not necessary for flanges to be provided on all 10 the edges, as, for example, they may be omitted entirely from the end section, here designated 1^a.

As shown in Fig. 12 an even more unobstructed interior may be secured by forming the box sections with outwardly offset 15 seats for the corner fastenings, whereby the inner faces of the inner members are brought substantially flush with the interior wall faces of the receptacle. These offsets are 20 preferably shaped to correspond to the form of the clamping members, as indicated at 18 in Fig. 13, and are further formed so as to fit 25 into each other when the sections are erected, thereby in effect keying the sections together preparatory to the application of the fasteners and contributing to the security of the structure as finally assembled.

It is to be understood that the term "container" is used generically and does not refer 30 to particular use.

What I claim as new is:

1. A container comprising separate wall or side sections, inward projecting edge flanges thereon, the sections having recesses 35 at the corners forming openings through the apical corners when the sections are set up

and one or more of the sections having entrances separating the ends of their flanges and leading to such openings, and corner fastenings comprising virtually pyramidal caps having apical recesses therein and inner members having diagonal projections adapted to extend through said openings into said recesses for connection with the caps. 40

2. A container comprising separate wall or side sections, inward projecting edge flanges thereon, the sections having recesses at the corners forming openings through the apical corners when the sections are set up, 50 said recesses having lateral entrances between the ends of the flanges of the sections, and corner fastenings comprising virtually pyramidal caps having apical recesses therein, and inner members having diagonal projections adapted to pass through said openings into said recesses for connection with the caps, said projections being larger at 55 their outer portions than said entrances and having reduced necks adapted to be accommodated therein in the assembling of the container. 60

3. In a container, the combination of separate wall or side sections, inward projecting marginal flanges thereon, and apical corner 65 fastenings comprising inner and outer virtually pyramidal members with means for uniting them diagonally through the corners of the assembled container, the flanged sections having outwardly-offset mutually-engaging seats for said fastening members. 70

ALBERT PAUL COCHRANE.
